United States Patent Office.

JAMES BRAHN, OF JERSEY CITY, NEW JERSEY.

Letters Patent No. 74,792, dated February 25, 1868.

IMPROVED SHOE FOR CAR-BRAKES.

The Schedule referred to in these Letters Patent and making part of the same.

TO ALL WHOM IT MAY CONCERN:

Be it known that I, JAMES BRAHN, of Jersey City, in the county of Hudson, and State of New Jersey, have invented a new and useful improvement in Attaching Shoes to Brake-Bars; and I do hereby declare that the following is a full, clear, and exact description thereof, which will enable others skilled in the art to make and use the same, reference being had to the accompanying drawings, forming part of this specification.

This invention relates to a new and improved manner of attaching shoes to the brake-bars of railroad-cars, whereby the shoes may be readily attached and detached, all bolts and screws being avoided, and the shoes, when attached, effectually prevented from being casually detached. The invention also relates to a peculiar application of India rubber to the shoes, whereby a requisite degree of elasticity is allowed the same, in order to prevent wear and tear. In the accompanying sheet of drawings—

Figure 1 is a side view of my invention.

Figure 2, a rear view of the same.

Figure 3, a section of the same taken in the line $x x$, fig. 2.

Similar letters of reference indicate corresponding parts.

A represents a plate of cast iron, slightly concave at its outer or face side, and provided with two horizontal flanges or lips $a a$, which are cast with it, and project at right angles from its rear side. Between these flanges or lips, the brake-bar (shown in red outline) is fitted and secured by one or more bolts. A plate, A, of this kind, is secured to each end of the brake-bar in line with the car-wheels, (shown in red.) The upper and lower ends $b b$ of the plate A are rounded, forming portions of a circle, the centre of which coincides with the centre of the plate. B represents a shoe, which longitudinally is of curved form, corresponding to the curvature of the tread of the car-wheel and the plate A. This shoe B is cast with two lips or projections $c c$, at its rear side, which have concave inner surfaces to receive the ends of the plate A. These concave inner surfaces also form the part of a circle corresponding to that of the ends $b b$ of plate A, so that, in order to fit the shoe B to the plate, all that is required is simply to apply the shoe to the plate in an oblique position therewith, as shown in red dotted lines in fig. 2, and turn the shoe, so that the ends of the plate A will pass into the sockets $c c$. This is all the fastening required to keep the shoe attached to the plate, for when the brake-bar is allowed to hang in the position designed for it in practice, the shoe B will be prevented from turning by the flange on the car-wheel. In order, therefore, to detach a shoe, B; the brake-bar must be pressed outward from the wheels, so that the shoe may clear the flange of the wheel, against the tread of which it presses when the brake is applied. The shoe may then be turned and detached from the plate. C represents a piece of India rubber, which is interposed between the shoe B and plate A. This rubber serves to keep the shoe firmly in position without play, and to admit of the shoe yielding to any irregularities on the tread of the wheel, thereby avoiding unnecessary wear and tear, and allowing the shoes, when necessary, to be more readily detached from the plates than they otherwise could be.

Having described my invention, I claim as new, and desire to secure by Letters Patent—

1. The shoe B, cast with sockets c , in combination with the plate A, formed with projections $b a$, substantially as described, for the purpose specified.
2. In combination with the above, I claim the rubber strip C, arranged substantially as and for the purpose set forth.
